CLAIM

The ornamental design for a microwave-safe box handle, as shown and described.

DESCRIPTION

FIG. 1 is a perspective view of the microwave-safe box handle embodying the design of the present invention; FIG. 2 is a front elevational view thereof, the rear being a mirror image of the front shown in FIG. 2; FIG. 3 is an end elevational view thereof, the end opposite being a mirror image of the end shown in FIG. 3; FIG. 4 is a top plan view thereof; and, FIG. 5 is a bottom view thereof.

FIG. 1

FIG. 3.

FIG. 2.

FIG. 4.

FIG. 5.
